AUTOMATIC CONTROL SYSTEM FOR LOCO-
MOTIVE WHISTLESPercy W. Smith and Charles S. Bushnell,
Rochester, N. Y., assignors to General Rail-
way Signal Company, Rochester, N. Y.

Application October 17, 1934, Serial No. 748,696

8 Claims. (Cl. 246—175)

This invention relates to a system for automatically controlling the sounding of a locomotive whistle upon the approach to highway crossings on railroads.

5 Generally speaking, in accordance with this invention, automatic means on the locomotive, having its operation initiated from the trackway upon the approach of the locomotive to a highway crossing, is employed to sound a locomotive whistle automatically, either giving a continuous blast until an engineman assumes control of the whistle, or a series of blasts characteristic of the warning signal commonly used for highway crossings.

10 15 Various characteristic features and advantages of the invention will be in part apparent and in part pointed out as the description progresses.

In the accompanying drawings, Fig. 1 illustrates in a simplified and diagrammatic manner 20 one embodiment of the invention, and Fig. 2 illustrates a modification.

Referring to Fig. 1, it is contemplated that a controlling impulse will be transmitted from the trackway to the locomotive by suitable means at 25 a predetermined distance from a highway crossing, preferably by inductive devices co-operating through an air-gap without physical contact. As illustrative of an impulse transmitting means suitable for this purpose, a trackway inductor 30 and locomotive carried receiver of the type disclosed for example in the prior patent to C. S. Bushnell, No. 1,686,434, October 2, 1928, has been illustrated diagrammatically; and since the principles and mode of operation of such an inductive impulse transmitting means are explained in said patent, a brief and general explanation will be sufficient for an understanding of the present invention.

The track inductor T is in effect an inert piece 40 of iron in the form of a U-shaped laminated core protected by a suitable non-magnetic housing, and is located at the side of the track with its pole faces above the level of the track rails and at a suitable distance from the highway crossing. 45 The locomotive receiver R comprises a U-shaped laminated core, having a primary coil P on one vertical leg, and a secondary coil S on the other leg. The primary coil P is energized from a generator G, or other suitable source of direct current on the locomotive, in series with a resistance 1, by a circuit readily traced on the drawings. A sensitive relay R1, preferably of the balanced type, such as disclosed in the patent to R. C. Leake, No. 1,696,170, December 18, 1928, is 50 normally energized by a stick circuit which may

be traced from a positive side of the generator, wire 2, front contact 3 of relay R1, wires 4 and 5, secondary coil S, wire 6, relay R1, and wire 7 to the lower terminal of the resistance 1. It will be evident that the relay R1 is energized by the drop 5 of voltage across the resistance R1 produced by the flow of current to the primary coil P.

When the receiver R on the locomotive passes over the track inductor T, a voltage is induced in the secondary coil S to de-energize the relay R1, 10 in the manner more fully explained in the prior Patent No. 1,686,434 above mentioned. In short, the relay R1 on the locomotive is automatically de-energized when the locomotive passes the track inductor T at a predetermined distance from the 15 crossing.

A relay R2 is energized by a circuit including a front contact of the relay R1, which may be traced from the positive terminal of the generator, wire 2, contact 3 of relay R1, wire 8, relay 20 R2, and wires 9 and 10 back to the other terminal of the generator.

Thus, whenever relay R1 is de-energized, its repeater relay R2 is de-energized.

It is contemplated that the sounding of the 25 steam whistle W on the locomotive will be controlled by an air operated valve V of suitable construction, and that the operation of this valve V in turn will be controlled by an electro-pneumatic valve EPV and by a hand-operated valve 30 HV within convenient reach of the engineman. In the particular arrangement shown, while the coil 12 of the electro-pneumatic valve EPV is energized, the whistle controlling valve V is connected to the hand valve HV, so that by depressing the hand lever 13, the valve 14 may be opened to supply pressure from the main reservoir to the valve V and cause the whistle to sound. When the electro-pneumatic valve EPV is de-energized, 35 main reservoir pressure is supplied directly to the valve V to sound the whistle.

The winding 12 of the electro-pneumatic valve EPV is energized by a circuit including a front contact of relay R2 which may be traced from the positive terminal of the generator, wires 15 and 45 16, front contact 17 of relay R2, wire 18, winding 12, and wires 19 and 10 back to the other terminal of the generator.

Thus, when the locomotive passes the track inductor T upon the approach to a highway 50 crossing, the de-energization of relays R1 and R2 causes de-energization of the electro-pneumatic valve EPV to sound the whistle, and the whistle will continue to sound until relay R1 is again energized.

Associated with the hand-operated valve HV are electrical contacts 20, closed when the lever 13 is depressed; and the closing of these contacts 20 establishes a shunt around the front contact 3 of relay R1, so that it may again pick up, this shunt also including contacts 22 of relay R2 closed when this relay is de-energized. The pick-up circuit for relay R1, including this shunt, may be traced from the positive terminal of the generator G, wires 15 and 21, contacts 22 of relay R2, wire 23, contacts 20 operated by the hand lever 13, wires 24 and 5, secondary coil S, wire 6, relay R1, and wire 7 back to the lower terminal of the resistance 1. Thus, when the blowing of the whistle is automatically started as the train passes the track inductor upon approaching the highway crossing, the engineman by operating the hand lever 13 to close contacts 20 may cause restoration of the relay R1, which is followed by energization of relays R2 and the electro-pneumatic valve EPV to stop the automatic blowing of the whistle. If the engineman is blowing the whistle at the time of passing the track inductor T by holding down the lever 13, the contacts 20 are closed and relays R1 and R2 are quickly restored, and the electro-pneumatic valve EP is de-energized only momentarily.

It will be evident that this invention provides for automatically sounding a whistle signal upon the approach to a crossing, even though the engineman is incapacitated or inattentive, or if he fails to note the approach to a crossing due to fog, or smoke. If the automatic sounding of the whistle occurs, the engineman may stop the continuous blast by operating the hand lever 13, and may thereafter sound the whistle in the usual series of blasts representing the signal for a highway crossing.

Fig. 2 illustrates another embodiment of the invention in which the locomotive whistle is automatically sounded in a series of blasts corresponding to the usual whistle signal for highway crossings, starting at a predetermined point distant from the crossing and continued as the train approaches the crossing in accordance with the distance travelled by the train. The engineman may at any time take over the automatic control of the whistle to delay or vary the whistle signal, or to stop the sounding of the whistle if the train should stop before reaching the crossing. This modified form of the invention adds in effect to the same devices illustrated in Fig. 1 apparatus for automatically energizing and de-energizing the electro-pneumatic valve controlling the whistle at predetermined intervals of distance during the approach of the train to the highway crossing.

Referring to Fig. 2, a shaft 25 is connected by a suitable transmission 26 to the axle 27 of the locomotive. A gear 28 on this shaft 25 meshes with an idler gear 29 carried on an arm 30, which is adapted to be raised by a spring 31 and pulled down by a starter magnet SM. When the starter SM is de-energized, and the arm 30 is raised by the spring 31, the idler gear 29 is meshed with a gear 32 on a cam shaft 33, so that this shaft 33 is rotated gradually in accordance with the distance travelled by the locomotive.

The cam shaft 33, as shown, is assumed to be rotated counter-clockwise; and spaced projections on a cam 34 carried by this shaft 33 closes contacts 35, these projections being spaced so that these contacts 35 are open for two long intervals followed by two short intervals, represent-

ing the two long and two short blasts of the whistle commonly employed for highway crossings.

After the cam shaft 33 has made approximately a complete revolution, a projection on cam 36 closes contacts 37 to mark the end of the operation and to cause the shaft to be restored to its normal position. The shaft 33 is restored to normal in the particular arrangement shown by a spring 38 connected to a flexible band 39 attached to a wheel or pulley 40 on the shaft, which is partially cut away to engage a stop 41.

In the modified arrangement of Fig. 2, relays R1 and R2 are energized by circuits and controlled in the same way as already described for Fig. 1. The parts are shown in the normal condition; and the electro-pneumatic valve is energized by a circuit from the positive side of the generators, wires 45 and 46, front contact 17 of relay R2, wires 47 and 48, valve EPV, and wires 49, 50, and 10 back to the other side of the generator. The starter magnet SM is also energized by a circuit from the positive side of the generator, wires 45 and 46, contact 17 and relay R2, wires 51 and wires 52, 50, and 10 back to the other side of the generator. The contacts 35 and 37 are normally open.

When the train passes the track inductor T, and relays R1 and R2 are de-energized in the manner already described, the EPV valve is de-energized to sound the whistle and at the same time the starting magnet SM is de-energized to connect the cam shaft 33 to the wheels of the locomotive. After the locomotive has advanced a predetermined distance, the first projection on the cam 34 closes the contacts 35 and establishes an auxiliary circuit for energizing the valve EPV which may be traced from the positive side of the generator, wires 45, 53 and 54, contacts 35, wire 48, valve EPV, and wires 49, 50, and 10 back to the other side of the generator. Thus, the whistle is silenced so long as the contacts 35 are closed; and after a further distance of travel these contacts open, and the whistle is again sounded. This same operation is repeated to give the blasts of the whistle to represent the highway crossing signal.

When the train reaches a predetermined distance from the crossing, the cam 36 closes the contacts 37, thereby establishing a shunt around the stick contacts of the relay R1 and providing a pick-up circuit for this relay which may be traced from the positive side of the generator, wires 45, 53, and 55, contacts 37, wires 56, 57, and 5, secondary coil S, wire 6, relay R1 and wire 7 to the lower terminal of the resistance 1. In this way, the relay R1 is again energized and its normal stick circuit is established; and the energization of relay R1 is followed by the energization of relay R2 and the starter magnet SM, thereby disconnecting the cam shaft 33 from the wheels of the locomotive, so that it may be returned to its normal or initial position by the spring 38, ready for the next operation.

The engineman, by operating the lever 13 of the hand valve HV, may close contacts 20 which, together with the wires 58 and 59, form a branch circuit in multiple with the contacts 37 and wires 55 and 56, so that the relay R1 is re-energized to restore the apparatus to normal. In other words, the engineer by operation of the lever 13 may at any time take charge of the blowing of the whistle, and restore the cam shaft 33 to normal. If the engineman should be blowing the whistle at the time relay R1 is de-energized upon passing

the track inductor T, this relay R1 is quickly restored, and the starting magnet SM is only momentarily de-energized if at all.

A system of this invention insures the sounding of a locomotive whistle upon the approach to a crossing, even though the engineman is inactive or incapacitated. It is contemplated that the automatic sounding of the whistle will start at a sufficient distance from the crossing with a 10 high speed train to provide ample warning time. The engineman may forestall or cancel the automatic sounding of the whistle, and regulate the duration and spacing of the blasts by hand in accordance with the speed of the train at a 15 certain distance from the crossing.

This particular structural organization as shown and described is merely illustrative of the nature of the invention; and various adaptations, and modifications, may be made without departing from the invention.

What we claim is:—

1. In a system for automatically sounding a locomotive whistle upon the approach to a highway crossing, means on the trackway a predetermined distance from a highway, means on the locomotive automatically initiated from the means on the trackway for sounding the locomotive whistle, and manually operable means for sounding the whistle and for rendering said automatic means inactive.

2. In a system of the character described, the combination with a track device located at a predetermined distance from a highway crossing, and a locomotive carried device influenced by the track device, of means on the locomotive having its operation automatically initiated by the cooperation of said devices for sounding the locomotive whistle, and manually operable means operable for sounding the whistle and restoring 40 said automatic means to its normal inactive condition.

3. In a system for controlling the operation of locomotive whistles, a normally energized relay on the locomotive, means responsive to the de-energization of said relay for automatically sounding the locomotive whistle, a manually operable device for sounding the whistle, means operated by said manually operable device for restoring said relay, and means partly on the 45 locomotive and partly along the track effective at a predetermined distance from the crossing for automatically de-energizing said relay.

4. A system for automatically controlling locomotive whistles comprising, a normally energized stick relay on the locomotive, a normally energized electro-pneumatic valve controlled by said relay and adapted when de-energized to sound 5 the locomotive whistle, a hand lever for controlling said whistle, contacts closed by movement of said lever to the whistle sounding position, a circuit for restoring said relay including said contacts, and means for automatically de-energizing 10 said relay at a predetermined distance from the crossing.

5. In a locomotive whistle controlling system, means on the locomotive driven from the wheels thereof and having its operation automatically 15 initiated from the trackway upon the approach of a locomotive to a highway crossing for sounding the locomotive whistle in a series of blasts, and manually operable means for restoring said means to normal.

6. In a system of the character described, means partly on the locomotive and partly on the track for transmitting controlling impulses from the trackway to the locomotive at a predetermined distance from a highway crossing, means 25 on the locomotive responsive to said impulses for sounding the locomotive whistle, and means also responsive to said impulses and driven from the wheels of the locomotive for silencing the whistle at predetermined points relative to the crossing. 30

7. A locomotive equipment for automatically sounding the whistle comprising, means having its operation automatically initiated from the trackway for sounding the whistle in a series of blasts in accordance with the distance travelled 35 by the locomotive, and manually operable means operable to sound the whistle and to restore said automatic means to its normal inactive condition.

8. A locomotive equipment for automatically 40 sounding the whistle comprising, means having its operation automatically initiated from the trackway for sounding the whistle in a series of blasts in accordance with the distance travelled by the locomotive, a second means for automatically silencing the whistle in accordance 45 with distance travelled, and manually operable means operable to sound the whistle and to restore said automatic means to its normal inactive condition. 50
